APPARATUS AND PROCESS FOR
CLEANING PLANTS

James Woodrow Swink, Effingham, S.C., assignor to Research Corporation, New York, N.Y., a non-profit corporation of New York

Filed Sept. 10, 1963, Ser. No. 307,861
7 Claims. (Cl. 131—138)

The present invention is broadly concerned with an improved process and apparatus for the cleaning and grading of tobacco plant leaves. The invention is more particularly concerned with an improved technique for processing cured tobacco leaves by the farmer or producer himself or tobacco leaves received by the processor in bulk form from the producer or the manufacturer. In accordance with the present process, foreign materials such as dirt, sand, string, feathers, etc., in cured tobacco are effectively and efficiently removed from tobacco leaves before being delivered by the producer to the market or warehouse by a unique integrated process and apparatus.

It is known in the art that one of the biggest and most vexing problems of the tobacco industry is the effective removal of foreign materials which comprise sand, string, feathers, grit and the like that are closely associated with tobacco when the tobacco leaves are delivered to the processor or to the market. Many solutions and techniques have been proposed, but thus far these proposals have not been economically effective. Thus, to a great extent, manual cleaning techniques are still utilized.

These foreign materials are appreciable and, in many instances, approximate about 5% of the total weight of the tobacco as it is purchased. Thus, one object of the present invention is to effectively and economically clean the tobacco when it comes directly from the curing barn so as to reduce these foreign materials to substantially zero. This cleaning of the tobacco is secured by utilizing a plurality of integrated processing operations. Another object is the mechanical grading and tying or bundling of the tobacco so that a uniform bundle, bale or pile is delivered to the market, processor or manufacturer.

These integrated operations, in essence, comprise a receiving operation, a humidifier operation and a loading-cleaning-grading operation and a tying or bundling operation. The particular adaptation of the present invention is to integrate the loading-cleaning-grading and tying or bundling operations into a plurality of stages by which substantially all of the undesirable materials or contaminants are effectively removed from the leaf tobacco in a very economical manner whereby the tobacco is properly graded.

The process of the present invention may be readily understood by reference to the drawings illustrating one embodiment of the same. FIGURE 1 generally diagrammatically illustrates the integrated operations; namely, receiving, humidifying and the loading-cleaning operation, while FIGURES 2a and 2b illustrates in some detail the integrated stages comprising the loading-cleaning and grading of the tobacco.

Referring specifically to FIGURE 1, the cured tobacco is delivered by the grower or producer to the receiving operation 1. The cured tobacco is received from the producer in bulk form and is not tied, but all the stem ends of the leaves are together.

After the tobacco has been received and handled at the receiving operation 1, it is passed to a process humidify-

2

ing operation 2 where the moisture content of the tobacco is raised and adjusted to the necessary level in order to get the tobacco in "order" for the succeeding operations. Effective control is maintained in order that the quality of the tobacco is not impaired by the introduction of too little moisture or too much moisture. Generally the moisture content should be in the range from about 20 to 25%. The tobacco is then normally passed to the loading-cleaning grading operation 3 wherein the same is graded into grades 1, 2, 3, and 4, as illustrated by the numeral 4. The graded tobacco is then passed into operation 5 where the tobacco is bundled and tied prior to transporting the tobacco to the ultimate purchaser 6. The predominant grade is passed to operation 7 and thence to the bundle and tying operation 5.

As is known in the art, the average number of grades of tobacco from one barn of tobacco is four, but quite often there are only two grades. However, there is always one predominant grade comprising approximately 20 to 60 or 70% of the tobacco from the same curing.

Referring specifically to FIGURES 2a and 2b, three basic stages of operation 3 of FIGURE 1 are illustrated; namely, a separation stage 10, a cleaning stage 11, and a grading stage 12. FIGURE 2a is a cross-sectional view of the operation, while FIGURE 2b is a top view of the operation. It is to be noted that separation stage 10 comprises a plurality of operational zones. For example, separation stage 10 comprises vibration zones 13, 14, and 15.

Thus, in the process, the tobacco leaves after removal from the humidifying operation 2 of FIGURE 1 are manually loaded upon a wire mesh conveyor belt 16 on a loading table 40. All the stems of the tobacco leaves are placed perpendicular to the line of travel with all the stem ends on the same side of the conveyor belt 16. This conveyor belt 16 in conjunction with other wire conveyor belts 17 and 18 will cause the tobacco to move progressively through the separation zone 10. Conveyor belts 17 and 18 are mounted on supported tables 41 and 42 respectively. In accordance with the present process, all three belts 16, 17, and 18 are vibrated. Furthermore, a distinct feature of the present invention is that all of these belts move at progressively greater velocities. For example, if the velocity of vibrating conveyor belt 16 is $V_A = A$ ft./sec., then the velocity of conveyor belt 17 is $V_B = V_A + K_1 V_A$ and the velocity of vibrating belt 18 will be $V_C = V_B + K_2 V_B$; where K is a multiplying constant.

Although the lengths of the respective conveying perforated belts 16, 17 and 18 may be varied appreciably and may be of equivalent lengths, a preferred adaptation is to have belt 16 longer than belt 17 and belt 17 longer than belt 18. Generally, it is preferred that the length of belt 17 be 60 to 90% of the length of belt 16, and that belt 18 be 60 to 90% of the length of belt 17. Also, the lengths of these belts could be adjusted in inverse ratio to the velocity of the respective belts. By utilizing this technique, more efficient cleaning and grading of the tobacco is secured. Furthermore, the height of vibrating belt 18 is below the height of vibrating belt 17 which, in turn, is below the height of vibrating belt 16. The difference in height is in the range from about 1 to 6".

Also, the velocities of the respective belts may vary widely depending upon various operating factors. However, it is generally preferred that the velocity in ft./sec. of vibrating belt 16 be in the range from about 7 to 17,

such as 12 ft./sec., and the velocity of vibrating belt 17 be in the range from 9 to 19, such as 14 ft./sec., and the velocity of vibrating belt 18 be in the range from about 11 to 21, such as 16 ft./sec. In zones 14 and 15, air jets 19 impinge upon the tobacco leaves and suction is established beneath belts 17 and 18 by suitable means through conduits 20 and 21. It is to be noted that the air jets in 14 impinge on the leaves, preferably off the vertical in different directions (plus and minus). Desirable angles of impinge off the vertical are from about 10 to 30° plus and minus. This aids in the separation and the positioning of the leaves. By operating as described, the tobacco leaves 30 which are loaded on vibrating belt 16 will tend to separate as illustrated in the top view as shown in FIGURE 2b. Thus, these conveyors 16, 17 and 18 moving progressively faster and vibrated as described cause the leaves to separate and thus permit the efficient removal of undesirable materials. The stream of air jets 19 impinging on these leaves aid the leaves to further separate. Thus, in passing through each of the different zones 13, 14, and 15, the leaves in zone 15 will be positioned so that only a single leaf will occupy a given position and no leaf will remain folded. In essence, the vibration and air streams initiate the cleaning operation causing the foreign matter to loosen and fall through the wire mesh for disposal. While it is preferred to vibrate the conveyors in the vertical plane, it is to be understood the conveyors may also be concurrently vibrated in a horizontal plane.

The leaves, now positioned on the conveyor only as single units, pass to cleaning stage 11 and onto a vibrating belt 22. The linear velocity of vibrating belt 22 is greater than the velocity of belt 18 as illustrated by the following formula: $V_D = V_C + K_3 V_B$. In stage 1, suction is applied both above and below the moving mesh screen by means of suction nozzles 23 and 43. Suction is applied through these nozzles by conventional means not shown. The relative suction pressures of nozzles 23 and nozzles 43 are so adjusted as to keep the respective leaves tightly adhered to the conveyor 22. These vacuum suction conduits mounted above and below the moving leaves will pick-up loose foreign matter such as sand, feathers, rubber bands, string and the like and thus produce a clean leaf without disturbing or distorting the alignment of the individual leaf on the conveyor. Another feature of the present invention is that the conveyor belts are cleaned on the return cycle. This removes any foreign matter that becomes entangled or enmeshed in the wire mesh which, if allowed to remain, would decrease the efficiency of the vacuum process.

Finally, the leaves pass into grading stage 12 and onto conveyor belt 24. In grading zone 12, the clean tobacco leaves pass under photoelectric cells 25, which cells are set in a conventional manner to detect different shades in the color and thus function to preferentially select leaves of different hues and colors. These photoelectric cells function through conventional relays and ancillary equipment which activate suction ports 26 so as to pick-up the various graded leaves in a predetermined pattern. It is to be understood that any number of photoelectric cells 25 and any number of suction pick-up nozzles 26 may be used. If four grades are to be selected in addition to the predominant grade, then four pick-up parts are used.

Under certain conditions, the final selection of two or more grades is preferably accomplished manually by an operator. The tobacco leaves that are not picked up and removed remain on the grading conveyor, are of one grade and will constitute the majority of leaves of predominant grade falling into a given grade of a single load or cure. These tobacco leaves constituting the predominant grade will continue along the conveyor and will be deposited into a container at the end of the belt. All grades are then bundled and tied automatically from which operation the bundles go to storage or are delivered directly to a purchaser or market.

Thus, the function of the present system and process is to produce clean and properly graded tobacco from cured tobacco received from the producer or purchaser. This is accomplished by an integrated plurality of processing steps which, in essence, comprise vibrating screens, preferably of different lengths and moving at progressively higher speeds and tied in with ancillary suction and pick-up means.

It is to be noted that in the separation stage wherein it is desirable to position a single leaf at one spot on the conveyor 18, suction is only applied to the underside of the screen, thereby permitting the leaves 30 to separate as illustrated in FIGURE 2b. This separation is secured by the cooperation of air jets preferably applied tangentially on the top of the leaves. In cleaning stage 11, on the other hand, after the leaves are secured or positioned at one spot on the screen, suction is applied both above and below the screen, which effectively removes the last traces of the undesirable contaminants.

Thus, the present invention is concerned with a unique integrated process for the effective cleaning of tobacco as it is delivered from the producer for the effective and rapid grading of the same and for the effective tying, bundling or bailing of tobacco.

What is claimed is:

1. Improved apparatus for the removal of foreign materials from tobacco leaves which comprises in combination a plurality of perforated conveyors suitably mounted in a separation stage, means for vertically vibrating said conveyors, suction means positioned below the intermediate conveyors, air jet means positioned above said intermediate conveyors whereby as the tobacco leaves pass from the initial conveyor to the secondary conveyor the leaves tend to space themselves one from another, suction means positioned above and below the final conveyor whereby as the tobacco leaves pass between the same foreign materials are removed, a plurality of photoelectric cells positioned in a grading stage, which cells in response to varying shades of color of the tobacco leaves activate pick-up means which pick-up the tobacco leaves of the different shades and separate the same one from the other.

2. Apparatus as defined by claim 1 wherein means are provided whereby said intermediate conveyors have a higher velocity than said initial conveyor and said final conveyor has a higher velocity than said intermediate conveyor.

3. Improved apparatus for the separation of foreign contaminants from tobacco leaves which comprises in combination an initial, a secondary and a tertiary perforated conveyor suitably mounted and positioned in a separation zone, a fourth conveyor positioned in a cleaning zone, means for vibrating all conveyors, suction means positioned below said secondary and said tertiary conveyor, air jet means positioned above said secondary and said tertiary conveyor, said jets so positioned as to impinge air jets on the tobacco leaves as they pass thereunder, suction means positioned above and below said fourth conveyor whereby as the tobacco leaves move from the initial to the fourth conveyor foreign contaminants are removed therefrom, a plurality of photoelectric cells positioned in a grading stage, which cells in response to varying shades of color of the tobacco leaves activate pick-up means which pick-up the tobacco leaves of the different shades and separate the same one from the other.

4. The apparatus as defined by claim 3 wherein the respective conveyors are positioned progressively lower as they move from said first to said fourth conveyor.

5. Apparatus as defined by claim 4 wherein means are provided to move the respective conveyors at progressively higher velocities from said first to said third conveyor.

6. Apparatus as defined by claim 5 wherein the length of the conveyor belts progressively decrease from said first to said third conveyor.

7. Process for the removal of contaminants from tobacco leaves which comprises passing the tobacco leaf at a progressively higher rate of speed from one zone to another and subjecting the same to vibration, subjecting the underside of the tobacco leaf to suction in a secondary and tertiary stage and impinging air jets on the top of the tobacco leaves in said secondary and said tertiary stages whereby the tobacco leaves tend to separate one from the other, thereafter subjecting the tobacco leaves on the top and underside to suction in a fourth stage, and thereafter passing the tobacco leaves beneath photoelectric

cell grading units whereby the different grades are picked up and graded as desired.
